UNITED STATES PATENT OFFICE.

HERRMANN R. BOISSIER, OF NEW YORK, N. Y.

BRUSH-HOLDER FOR DYNAMO-ELECTRIC MACHINES.

SPECIFICATION forming part of Letters Patent No. 310,780, dated January 13, 1885.

Application filed May 13, 1882. (No model.) Patented in England January 22, 1883, No. 357; in France January 22, 1883, No. 153,253; in Belgium January 22, 1883, No. 60,233; in Germany January 24, 1883, No. 25,295; and in Austria August 7, 1883, No. 4,289.

To all whom it may concern:

Be it known that I, HERRMANN R. BOISSIER, of New York, in the county of New York and State of New York, have invented a new and useful Improvement in Dynamo or Magneto Electric Machines; and I do hereby declare that the following is a full and exact description of the same, reference being had to the accompanying drawings, and to the letters of reference marked thereon.

My invention relates to the commutator-brush holders of dynamo and magneto electric machines; and its object is to provide a brush-holder of such construction that the brush may be readily adjusted therein, and yet be held firmly and securely in the desired position, and to so protect the clamping devices and the brush that they may be handled without danger of accidental shocks; to which ends it consists in the features more particularly hereinafter described and claimed.

In carrying the invention into effect the brush-holder is made as a frame with open sides, within which a follower is arranged to travel, it being adapted to press and hold the brush upon the bottom of the frame. Upon the sides of the follower two projections rise, in which are pivoted a rod carrying a cam or eccentric shaped on its two sides and lower end as a parallelogram, while the upper end is formed into a curve, such as the one shown, or a similar one. Upon the under side of the upper part of the brush-holder is a spring. The rod upon which the eccentric is mounted is prolonged beyond the carrier, and terminates in a knob, preferably rubber-coated or otherwise insulated. When this rod is turned so that the longer sides of the eccentric are parallel to the brush, the follower is so loosened that the brush may be freely moved therein. When it is adjusted, a quarter-turn of the rod brings the eccentric so that its upper curved end presses against the spring above it, and by means of the rod passing through the ears attached to the follower it presses the latter down upon the brush, holding it securely, the upper end taking against the spring, which, fitting slightly into the curve mentioned, holds the eccentric against accidental displacement.

The outer end of the brush, which is prefer-

ably composed of several strips or wires, is covered with rubber or other good insulator, so that it may be handled without danger of shock. Such an arrangement is shown in the drawings, wherein—

Figure 1 is a side, and Fig. 2 a top, view of a brush-holder embodying the invention. Figs. 3 and 4 are end views showing the eccentric in different positions, and Fig. 5 a view showing the preferred form of the eccentric.

C is the frame of the brush-holder, provided with a projection or lug, L, for attachment to the machine. The frame C is composed of a bottom, a, sides c c, and top b. Within the rectangular opening thus formed plays the follower D, upon the sides of which lugs d are formed, furnishing a support and pivots for the rod A, which is prolonged and terminated in the rubber or insulated knob B. Upon this rod, and between the supports d d, is secured the cam e, formed with two long parallel sides and a base at right angles thereto, while the top is formed as a curve having two slightly-elevated curves, x x, with a concavity, y, between them. Upon the under part of the top b of the brush-frame is secured the spring r. When the rod A is turned so that the eccentric is in the position shown in Fig. 3, the follower is released, so that the brush H may be inserted or moved to any desired position between D and a. When H is adjusted, the rod A is given a one-fourth turn, which brings e into the position shown in Fig. 4, the upper part taking against the spring, the pressure being transmitted to the follower, which grips the brush H by means of the pivots formed by the rod A passing through the cam and ears of follower. The bottom of the cam clears the top of the follower, so as not to interfere with its action. From the shape of the top the spring bears upon x x, and holds it positively and firmly against accidental displacement. The free end of the brush H is covered with rubber or other good insulator, I. The rod A being protected at its end by the knob B and the brush by its coating I, all danger of shock while adjusting or changing the brush is avoided.

The devices described enable the brush to be

rapidly and easily put in position or adjusted, the minimum of manipulation being required to loosen or to tighten the brush.

While I have here shown and described the 5 preferable means for carrying my invention into effect, it is obvious that it may be varied in many ways without departing from the principle thereof. For example, the form of the 10 cam might be varied in many ways, or the rod controlling it might be mounted in bearings independent of the follower, and many other changes might be made.

What I claim is—

1. A brush-holder for a dynamo or magneto 15 electric machine, consisting of a frame, a follower sliding therein, and an eccentric or cam for operating the follower, substantially as set forth.
2. A brush-holder for a dynamo or magneto

electric machine, consisting of a frame, a fol- 20 lower capable of sliding therein, and an eccentric or cam for operating the follower, mounted upon a rod having its bearings in lugs upon the follower, substantially as set forth.

3. In a dynamo or magneto electric machine, 25 the combination of an eccentric having its top composed of three curves, the middle one being concave, as shown, with a spring adapted to take in such curve and hold the same in position with the frame and follower of a 30 brush-holder, all substantially as shown and set forth.

This specification signed and witnessed this 9th day of May, 1882.

HERRMANN R. BOISSIER.
